UNITED STATES PATENT OFFICE

121,794

DESIGN FOR A CONFECTIONERY BOOTH

Emmett R. Rogers, Chattanooga, Tenn.

Application October 27, 1938, Serial No. 80,711

Term of patent 3½ years

To all whom it may concern:

Be it known that I, Emmett R. Rogers, a citizen of the United States and a resident of Chattanooga, in the county of Hamilton and the State of Tennessee, have invented a new, original, and ornamental Design for a Confectionery Booth, of which the following is a specification, reference being had to the accompanying drawing, forming part thereof.

I claim:

The ornamental design for a confectionery booth or similar article, substantially as shown.

EMMETT R. ROGERS.
